UNITED STATES PATENT OFFICE.

AARON SERFOSS, OF ASHLEY, PENNSYLVANIA.

RIGHT AND LEFT CALKING-TOOL.

938,173.

Specification of Letters Patent. Patented Oct. 26, 1909.

Application filed March 24, 1909. Serial No. 485,561.

To all whom it may concern:

Be it known that I, AARON SERFOSS, a citizen of the United States, residing in Ashley, in the county of Luzerne and State of Pennsylvania, have invented new and useful Right and Left Calking-Tools, of which the following is a specification.

My invention relates to improvements in right and left calking tools, in which two tools only are used in making that part of a joint in soil pipe which is out of reach of ordinary calking irons and hammer, when the pipe runs up in a corner of a building or a recess in a brick wall, as is almost invariably the case. I attain this object by the tools illustrated in the accompanying drawing, in which—

Figure 1 represents a front and side view of the right and left calking hammer; Fig. 2 represents a front and side view of the right and left hemping hammer.

Similar letters refer to similar parts throughout the several views.

The right and left calking hammer shown in Fig. 1 is the same in all respects to the right and left hemping hammer shown in Fig. 2, excepting the head; A being the head of the calking hammer and D being the head of the hemping hammer. The handle B C is common to both calking and hemping ham-

mers. B is made of wrought steel and C of wood.

The head D of the right and left hemping hammer, Fig. 2, is narrowed at the ends, in order to drive the hemp down into the bell of the pipe. The ends are made symmetrical with respect to the handle B C. 35

The head A of the right and left calking hammer is made thicker at the ends than the head D of the right and left hemping hammer. The ends of the head A are also made symmetrical with respect to the handle B C. 40

The wrought iron part of the handle B C is curved, the radius of the curve being one half the outside diameter of standard soil pipe. 45

I claim—

A calking tool for pipe joints comprising an elongated hammer head having a narrow or thin calking blade at each of its ends and a handle having a curved end secured to the side of the head at a point intermediate the ends and extending from said head in a plane parallel with the operative edges of the blade, substantially as described. 50 55
